COMBINED FOOD WARMER AND DISPLAY DEVICE

Tony J. Bressickello, 13015 S. Normandie Ave.,
Gardena, Calif. 90249

Filed Oct. 20, 1966, Ser. No. 4,353

Term of patent 14 years

(Cl. D81—10)

FIG. 1

FIG. 2

FIG. 3

FIG. 4

FIG. 5

FIGURE 1 is a perspective view of a combined food warmer and display device showing my new design;

FIGURE 2 is a front elevational view thereof;

FIGURE 3 is a side elevational view thereof;

FIGURE 4 is a rear elevational view thereof; and,

FIGURE 5 is a top plan view thereof.

I claim:

The ornamental design for a combined food warmer and display device, substantially as shown.
